yarns pass to the knitting mechanism, not shown.

The numeral 25 denotes a controller mechanism of known construction, shown diagrammatically. For example, the mechanism shown in the U. S. Patent 2,222,325, November 19, 1940, may be used. The principal elements in the controller 25 are a stop handle 26 which is held in operating position by a holding member 27. In this position the stop handle keeps a shifting lever in running position, i.e. the knitting machine is operating. The holding member is in known manner locked to the stop handle by a pivoted armature 29 operated by a magnet 30. When the magnet is energized, the armature 29 is attracted to release the member 27 from the stop handle. The latter is then moved by a spring 31 to shift the shifting lever 28 and the knitting machine stops.

The electric circuit is as follows. The main supply line leads to a transformer 33. One side of the transformer is connected by wire 34 to the feeder post 48 and to the ring 15. The double connection to the post and to the ring is merely a matter of precaution. The current passes through the distributor ring and to a wire 35 from which the devices 13 and 14, and other devices, not shown, are supplied with current. The devices are all grounded on the machine in known manner. An electric lamp 36 is mounted on a prominent part of the knitting machine to serve as a signal. One side of the lamp is grounded. The other side is connected by a wire 37 to the magnet 30. The latter is connected to the transformer as shown.

If a yarn fails in passing normally through any one of the detector devices, the latter will automatically operate to close the circuit. Thus the magnet will be energized and the machine will stop so the trouble can be attended to.

The closing of the circuit through the magnet also causes the lamp to be lighted so that it will serve as a signal to the operator that a particular machine requires attention. The operator usually attends several knitting machines arranged close to each other. The lighting of the lamp, which preferably is provided with a red bulb, constitutes a prominent signal to be seen through the maze of operating parts of several machines. The lamp also serves as a signal in the event the current output of the transformer is too weak to operate the magnet, yet is strong enough to light the lamp. In such case the signal will serve as a warning to examine and test the transformer. Then again, the controller may for some reason be out of order or have worn parts. In such case the circuit will be opened only momentarily. The lamp will then again be lit and warn the operator. It also happens that the structure of the yarn is faulty so that a detector device is operated only to such an extent that the circuit is closed by a mere-touch movement. In such case the lamp will flicker as the faulty yarn passes through the detector. Should the yarn break or should too much slack occur below the bobbin table, the spring 21 will snap upward and contact the rotating ring to close the circuit.

The distributor ring consists of a stationary ring 15 which, as shown in Figs. 3 and 4, is provided with a centrally disposed downwardly projecting rail 40. On both sides of the rail there are lateral contact surfaces 41. The inner side of the ring is formed with an overhanging flange 42. The stationary ring rests upon the rotating ring 16. The latter has complementary lateral contact surfaces 44 opposite the surfaces 41 and a groove 45 which receives the rail 40. The con-

tact surfaces, the rail and the groove in the two rings are fitted closely to provide good electric contact from the stationary ring to the rotating ring. The contacting surfaces are oiled through oil cups 47, Fig. 2, to insure smooth running in spite of the close fit. The arrangement is such that while the rotating ring may move with whatever speed the knitting operation requires, the electric contact between the two rings remain unbroken and a steady flow of current is maintained.

The ring has four hanger brackets 17 as seen in Fig. 2. The hanger brackets are preferably a part of the ring. Each bracket is insulated from the machine as at 48. Each bracket also carries a wire terminal 49 for attaching the wires which lead to the several electric devices on the machine. Each hanger is apertured to receive an arm 11, see Fig. 1, and is kept in position by a set screw 43. Another screw 51 secures the insulation 48 in place and serves to keep the insulation in position to press down upon a finger piece 52 which overlays the stationary ring and prevent vertical separation of the two rings.

Current is delivered to the stationary ring by contact with the feed posts 48. Wires as 35 may also be attached directly to the ring. The feed posts are fixed and thus serve to prevent rotation of the stationary ring which otherwise might be rotated by contact with the rotating ring. Hence the posts are placed on the far side of contact lugs 50 with respect to the direction of rotation of the ring 16, see arrow 53 in Fig. 2. The feed posts 48 are also spaced away from contact with the flange 42, note the space 54 in Fig. 7. This is to allow the ring, as a whole, to sway and move, and vibrate laterally and thereby follow the motions of the rotating elements. The ring is floating with respect to the feed posts. Thus binding or jamming is avoided.

Figs. 5 and 8 show a distributor ring in which the stationary ring 15 has an additional overhanging flange 56 on the outer side of the ring for greater protection against dirt. In Fig. 8, therefore, the hanger bracket 57 is formed to permit it to rotate freely with respect to the ring flange. Note the space 58 in this figure. Fig. 6 shows a ring structure in which balls 60 run in grooves between the stationary ring 61 and the rotating ring 62.

There may be knitting machines so constructed that only a very small distributor ring can be applied. In such cases the construction shown in Fig. 9 may be used. The ring element is secured directly to the central rotating shaft 10. Either of the above described ring constructions may be used, but for the sake of simplicity in illustration the ball and groove ring in Fig. 6 is shown. In Fig. 9 the rotating ring 10 is contained within a cage 71 which forms a sleeve 72 with holes 73 for the passage of the yarns from the detector devices. The stationary ring 74 is contained within a cage 75 which has flanges 76 and 77 to prevent dirt from entering between the two rings. The latter have grooves to receive the balls 78. The sleeve 72 is secured to the shaft 10 by a set screw or pin 79 and carries a terminal 80 for attaching the wires which are led to the detector devices. An insulating liner 82 is interposed between the shaft and the sleeve.

The distributor ring according to this invention is easily secured to the machine by merely detaching the arms 11 and then passing them through the hanger brackets. The ring is prac-

tically indestructible and accomplishes the object sought in a most efficient manner.

I claim:

1. An electric distributor ring for a rotary knitting machine consisting of two electric conducting rings, one of which rotates upon the other ring in close contacting electric current conducting relation therewith, a hanger bracket on said rotating ring for attaching the same to the knitting machine to rotate therewith, a finger piece 10 supported on said bracket and overlapping the stationary ring to prevent separation of the said two rings and means on said hanger bracket for maintaining said finger piece in the said overlapping relation to the stationary ring.

2. An electric distributor ring for a rotary knitting machine having detachable bobbin supporting arms, a hanger bracket on said distributor ring having an aperture to receive one of said

arms for attaching the ring thereto and means for securing the hanger bracket to the said arm.

3. An electric distributor ring for a rotary knitting machine consisting of two electric conducting rings, one of which rotates upon the other in current conducting relation, means for attaching the rotating ring to the knitting machine to rotate therewith, a feeder post, means for supplying electric current to said post, a lug on said stationary ring adapted to engage said feeder post in the direction of rotation of said rotating ring to receive electric current from the post, said post being spaced from said distributor ring to permit the latter to move vertically with respect to said post without interrupting the contacting relation between the post and the lug on the stationary ring.

MICHAEL WACHSMAN.
